UNITED STATES PATENT OFFICE.

JOSEPH E. BURGE, OF DENVER, COLORADO.

COMBINED CHAIR AND DESK ATTACHMENT.

1,023,620.

Specification of Letters Patent.

Patented Apr. 16, 1912.

Application filed February 18, 1910. Serial No. 544,538.

To all whom it may concern:

Be it known that I, JOSEPH E. BURGE, a citizen of the United States, residing at Denver, in the county of Denver and State 5 of Colorado, have invented certain new and useful Improvements in Combined Chair and Desk Attachments, of which the following is a specification.

This invention relates to combination furniture in the form of a desk and seat and more particularly to a device of this character adapted for the use of stenographers, and the invention has for its object the provision of a combined seat and typewriter 15 stand attachment, though I wish to reserve the right to manufacture the chair independent of the stand, whereby the chair may be used as an ordinary office chair.

An object of the invention is to provide 20 a device of this character in which the stand attachment will be supported in such relative position to the chair; which is of cushion form, that such attachments provided for the stand, will be convenient for the use of 25 the operator. It is to be understood that such attachments are for holding stationery, pencils and other necessities, as clearly understood.

A further object of the invention is to 30 provide a novel form of seat, of cushion form, which will be much more restful for any person whose occupation requires them to be in a chair for any length of time.

A further object is the provision of a desk 35 or stand attachment and novel means for securing the same to the chair, so as to do away with an expensive desk and chair, at the same time providing a device which will be complete in itself, so positioning the 40 stationery, letters, note books, and other necessities, in convenient position to the operator for use.

A still further object is the provision of a device which can be constructed of a minimum 45 amount of material, so as to take up a small amount of space, and which can be constructed at a low cost.

Other objects and advantages will be apparent from the following description and 50 it will be understood that changes in the specific structure shown and described may be made within the scope of the claim without departing from the spirit of the invention.

In the drawings: Figure 1 is a perspective view showing the desk and seat secured in position for use, and also showing the attachments thereto, by which the stationery and the like are supported for ready use. Fig. 2 is an underside view of the seat showing the spring cushion attachment thereto. Fig. 3 is a vertical central sectional view of the supporting member for the seat, showing the relative connection of the parts and the interior supporting spring. Fig. 4 is a detail view of the standard showing the position of the grooves thereon, said grooves being adapted for engagement with the movable upper portion carried by the seat. Fig. 5 is a detail view of a sleeve for adjusting the vertical position of the spindle. Fig. 6 is a detail view showing the manner of pivoting the upper portion of the arm extension of the stand to the lower portion thereof. Fig. 7 is a view of the under side 75 of the desk board, showing its attached parts in different relative positions and the supporting arm in section. Fig. 8 is a central longitudinal sectional view of the spring cushion attachment, detached from the seat. 80

In the drawings I have shown a seat 10, to the under side of which is secured a depending bracket 11, which comprises a base portion which is positioned parallel with relation to the bottom of the seat and has its 85 central portion cut away as shown at 12, longitudinally thereof, the tongues formed by said cut-away portion being extended inwardly for engagement with the bottom face of the seat. The said inturned portions form ribs adapted to brace the bracket adjacent the sides of the openings, said inturned portions 13 being positioned in engagement with the under face of the seat and secured thereto through the medium of 90 the outturned portions 14, the ends 15 of the brackets being extended upwardly at an angle to the central portion and said ends are provided with apertures through the medium of which said bracket is secured 95 to the seat, and as also shown one of the ends is provided with an opening communicating with the central opening of the bracket, said opening being adapted to receive a suitable spring 16 when in position, as will be hereinafter more fully described.

Pivotal secured to a transverse rod mounted on the inturned portions of the

bracket centrally thereof, is an intermediate arm 17, said arm having upturned flanges 18 which are pivotally engaged with the pivot rod and are adapted to ride within the slot. The base of said intermediate member is provided with a downwardly extended arm or extension 19, said arm being provided with an aperture 20, adjacent its lower end, which aperture and the corresponding aperture 21 at the side of the bracket positioned over the extension, are adapted to receive the downturned and upturned ends 22 of the spring 16, said spring being coiled at its restricted end so as to resist the weight 15 of a person when seated in the chair. The arm 17 is further provided with a slotted opening communicating with the central opening in the bracket, and it will be seen that when the spring is in position and under the weight of a person sitting in the chair, the arms of said spring will be compressed and forced into these openings allowing sufficient movement to the parts when under a severe strain, though it is to 20 be understood that the resiliency of this spring is such as to permit free and even movement of the parts of the chair when the same are under a strain or released therefrom.

30 The base of the arm has secured thereto a depending stem 23, which is provided with an enlarged or flared upper portion 24, adapting the same to be secured to said base portion, and as shown, I have provided 35 this flared portion with openings through which the fastening means can be passed into engagement with the base portion, whereby said parts are rigidly held together. This depending stem 23 is screw threaded, a 40 greater portion of its length, and is received within an opening in the upper part of the sleeve, the upper portion 26 of which is formed of solid material, with the exception of the opening through said portion into 45 which the stem 23 is adapted to work. The lower portion of the sleeve is hollowed a greater portion of its interior diameter and has inwardly extending lugs 27 for engagement with the grooves 28, formed in the 50 upwardly extending stem 29, said grooves extending vertically of the opposite sides of the sleeves and terminating short of both ends thereof, said grooves being also extended at right angles adjacent to the upper ends thereof, one quarter of the distance around the sleeves and then upwardly to the end of the cylinder, it being apparent that the lugs 27 will be applied simultaneously to said grooves and slid thereinto 55 for positioning the sleeves 25 and the seat carried thereby onto the stem 29, said lugs being prevented from withdrawal therefrom when lifted vertically, but being removable through the medium of the right angular extended portion. The upper end of the

sleeve 25 has an outwardly extending lip 30, upon which rests a suitable adjusting nut 31 when in its lowermost position. The depending stem 23, fits snugly within the upper portion of the sleeve 25, so as to prevent wabbling of the seat and this stem is engaged by the adjusting nut 31, movable thereon and adapted to adjust the height of the chair seat, it being understood that such adjustment is regulated by the position of the nut on the stem, so that further downward movement thereof is prevented. This nut has a flanged rim 33 at its lower end which rests upon the lip 30, said nuts being formed in two parts hinged together 75 upon opposite sides, so that the same may be readily applied to or removed from the stem and when said parts are in closed position they are secured by means of set screws, the flanged portion thereof being adapted to fit under the edge of the lip, so as to prevent the chair from being pulled apart when lifted. The sleeve portion of the adjusting nut, is provided with internal screw threads engageable with the screw 90 threads on the stem 23. Said sleeve is provided with a set screw 32 extending transversely therethrough to engage with the screw threads on the stem, whereby it can be held in any position on the stem and the 95 stem thereby held in such position. It is understood that when it is desired to raise or lower the chair the adjusting screw is rotated for disengagement with the threads on the stem 23, whereby the member 23 may 100 be moved to any desired position within the sleeve 33 and held by means of the set screw, it being understood that the flanged portion 81 may be retained into engagement with the lip 30 formed on the upper end of 105 the sleeve 25.

The lower end of the stem 29 is enlarged for a portion of its length, as shown at 34, and said enlarged portion is provided at equal distances around its periphery, with 110 outwardly extending sockets 35, said sockets being secured to or formed integral with the front portion 34 and have received therein the usual legs 36. I have provided four of such legs, though any number thereof 115 may be provided and the outer ends thereof have the usual rollers 37, so that the chair may be readily moved about the floor. The stem 29, above the enlarged portion 34, is hollowed out from its upper end, as shown 120 at 38, and a coil spring 39 is disposed therein, around the depending stem 23, said spring being positioned intermediate the sleeve 25 and the bottom of the hollowed out portion of the stem, so as to hold the 125 sleeve in a normally distended position, the inwardly extended lugs 27 being adapted to slide within the grooves 28 upon relative movement of the two parts. Fitting snugly into the top of the stem 29 is a ring 6, said 130

ring being provided with a rim extending outwardly therefrom at its upper portion, so as to fit closely within the sleeve 25, to take up wear upon the parts and to prevent 5 wabbling thereof.

Disposed above the enlarged portion 34 of the stem, is a collar 40, said collar being disposed around the stem below the sleeve 25 and adapted to rest upon a shoulder formed 10 by the enlarged portion 34 with the smaller portion of the stem, and as said parts are preferably of cast material, it is more especially desired that the upper face of this enlarged portion forming the shoulder, be 15 formed with a polished bearing surface for the collar 40, which is adapted to move thereon and said collar has secured thereover and disposed upon the stem 29, a securing sleeve 41, which is positioned to contact with the upper edge of the collar 40, to securely hold the same in its lowermost position and in contact with the shoulder, so that the stand casting 42 formed therewith will be held against play thereon. This 20 stand casting 42 is rotatable on the stem 29, through the medium of the collar 40, and is in the form of an arm extending outwardly from the collar and curved downwardly so as to position the same near the floor, said 25 arm is then extended upwardly a proper distance, the upper end of said arm being bifurcated for the reception of the lower end of the standard connecting portion 43. At a point on the casting, adjacent to the floor, 30 two feet 44 are secured on either side thereof, said feet being secured to the casting in any desirable manner, the lower ends of the feet being provided with the usual bearing rollers, so as to allow the casting to be 35 moved to any desired position. The object of the feet is to prevent the weight of the typewriter supporting stand from overturning the chair.

The bifurcated arms 45, have their interior side faces notched as shown at 46, and said arms are provided with registering openings extending transversely therethrough, said openings being adapted to receive a suitable securing bolt 47, which is also passed through the lower notched end of the connecting standard 43. The lower end of the connecting standard 43 is reduced laterally to form a tongue 48, which, as before mentioned, is notched upon either side thereof, all of said notches being disposed in a circular position around the openings, with which the tongue 48 is also provided, and the bolt is provided with a securing nut 49, so that by rotating said nut in one direction the forcive contact of the notched faces will be lessened and the connecting standard 43 may be swung at any desired angle relative to the arm or casting, but 60 still be held in a very rigid position.

65 Secured to the outer flared end of the con-

necting portion 43 is a desk board 50, upon which the typewriter is adapted to be supported and held in a rigid position in the usual manner. The desk board has secured to its under surface adjacent said end, a collapsible frame, said frame being composed of a plurality of bars 52 extending outwardly therefrom, a plurality of cross members 53 provided therefor centrally thereof and at each end, said parts being pivotally connected where crossed, the frame being pivotally mounted at the side of the board, so that the same may be folded and slid under the stand. On the left hand side of the board is a similar but smaller frame 51, it being understood that a basket or a board for holding mail or other papers may be supported thereon, when extended. Secured to the under face of the board adjacent the left hand side and at the forward end thereof, is a box 54, which is pivotally secured thereto and adapted to be swung outward, this box being adapted for the reception of pens, pencils, etc. Disposed at the right hand corner of the board and adapted to be pivotally mounted in a similar manner to said board is a case 55, which extends over the greater portion of the board, this case being preferably constructed of metal and divided into compartments, for the reception of writing material, etc.

The manner of adjusting the seat and the desk board, having been previously described, it will thus be seen that I have provided a cushion frame chair and stand attachment, which will do away with the use of an expensive desk and chair, the device being so complete in itself that there will be no need of other furniture or place for handling the work, the operator being able to keep stationery, letters, note books, pencils, and all other necessaries in a position to be readily procured when desired.

I wish to have it understood that I may manufacture this device with or without the stand attachment, it being understood that the same may be manufactured in sizes to suit the requirements, that is; whether used as a stenographer's chair or as an ordinary office chair, though I wish to have it understood that the same principle may be applied to any form of chair.

What is claimed is:

A tilting chair comprising a seat, a bracket formed from a single piece of metal and comprising a base portion being cut-away longitudinally to form tongues, said tongues being bent inwardly for engagement with the seat, the ends of said bracket being extended upwardly and at an angle to the base portion and secured to the seat, an arm having a pair of upturned parallel flanges adapted to rock within the cut-away portion of the base, said flanges being pivotally connected to the inwardly bent tongues of the

base portion, an extension formed integral with the arm, a spring arranged between the extension and one of the extended ends of the bracket, means for holding the spring against accidental displacement, a stem secured to the arm and means for adjustably supporting said stem.

In testimony whereof I affix my signature, in presence of two witnesses.

JOSEPH E. BURGE.
